SHOE HEEL REINFORCEMENT

Louis Sabo, Bronx, and Joseph Kiss, New York,
N. Y.

Application June 30, 1938, Serial No. 216,638

3 Claims. (Cl. 36—76)

This invention relates to new and useful improvements in a heel reinforcement.

More specifically, the invention proposes the construction of a heel reinforcement characterized by a strip of material engageable upon the curved side of a shoe sole at the point of connection between the heel and the sole for reinforcing this area to maintain the heel in position upon the shoe.

10 Still further it is proposed to provide the ends of the strip of material with openings through which fastening elements are adapted to be engaged for holding the strip in position thereon.

Still further it is proposed to provide the face 15 of the strip of material adjacent the curved side with a hollowed out portion into which a stiff member is engaged and which has its ends extending from the sides of the member for engaging the areas of the curved side for assisting 20 the strip of material in maintaining the heel in position.

Still further it is proposed to construct the strip of material with a removable central section having tongues engaging complementary recesses in the end sections when the sections are 25 engaged.

A further object of this invention is to provide a set screw engaged through the central section for engaging against the top face of the stiff member 30 for clamping the sections of the strip of material together and for holding the stiff member in position within the hollowed out area.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a bottom perspective view of a shoe having a heel reinforcement constructed according to this invention.

Fig. 2 is a perspective view of the heel reinforcement per se.

Fig. 3 is a view similar to Fig. 1 but illustrating a modification of the invention.

Fig. 4 is an enlarged sectional view on the line 4—4 of Fig. 3.

Fig. 5 is a perspective view of a heel reinforcement constructed according to a still further modification of the invention.

Fig. 6 is a sectional view on the line 6—6 of Fig. 5.

Fig. 7 is a similar view to Fig. 1 but illustrating a still further modification of the invention.

The heel reinforcement, according to this invention, is to be used in combination with a shoe 10 having a sole 10^a extending along the bottom thereof and across a portion of the arch thereof. A high heel 10^b is attached to the bottom of the shoe 10 at the back thereof and has a face 10^c at substantially right angles to the plane of the sole 10^a of the shoe 10. At one end of the face 10^c 10 adjacent the end of the heel which is attached to the shoe 10 and the heel 10^b continues into a thin area portion 10^{cc}. A portion 10^{aa} of the sole 10^a extends rearwards to the heel 10^b and then downwards along the face 10^c of the heel. 15

The heel reinforcement is characterized by a strip of strong material 11 which is engaged over the adjacent ends of the thin area portion 10^{cc} and the sole 10^a. The strip of strong material 11 is formed with a roughened outer face 11^a which 20 permits the adjacent face of the portion 10^{aa} of the sole 10^a to be securely attached thereto.

Fastening elements 12 are adapted to be engaged through openings 11^b formed in the ends of the strip of strong material 11. The fastening 25 elements 12 are in the form of screws or similar elements and are adapted to be threadedly engaged into the shoe 10 for clamping the said adjacent ends together as a rigid unit. That portion of the face of the strip of strong material 11 30 adjacent the said ends between the openings 11^b is cut away to form a hollowed out area 11^c forming a space between the adjacent face of the hollowed out portion and the curved side 10^c.

According to the modification of the invention 35 shown in Figs. 3 and 4 the construction of the heel reinforcement is similar to that previously described and the attachment thereof is also the same, distinguishing therefrom by the inclusion of a stiff member 13 engaged into the space 40 formed by the hollowed out portion 11^c in the strip of strong material 11^b. As shown in Fig. 3, the sides of the stiff member 13 extend beyond the sides of the strip of strong material 11 engaging the areas of the thin portion 10^{cc} and the 45 adjacent portion of the sole 10^a for assisting the strip of strong material in clamping the heel 10^b in position upon the shoe 10. In other respects this form of the invention is similar to the previous form.

According to the modification of the invention 50 shown in Figs. 5 and 6 the construction of the heel reinforcement is similar to that described relative to Figs. 3 and 4 and differs therefrom in that the strip of strong material 11 is formed of sep- 55

arate sections. The separate section forming the strip of strong material comprise end sections 11^d and a central section 11^e. The central section 11^e is formed at its ends with tongues 14 which are adapted to engage into complementary recesses 15 formed on the adjacent inner faces of the end sections 11^d. This construction permits the central section 11^e to be removed from the end sections 11^d by slipping the same through the sides thereof.

10 A means is provided for clamping the stiff member 13 in position against the thin portion 10^{cc} and for holding the central section 11^e in position between the end sections 11^d. This means 15 comprises a set screw 16 threadedly engaged through the central section 11^e and bearing against the adjacent face of the stiff member 13.

The operation of this device is as follows:

20 For assembling the heel reinforcement, according to this form of the invention, the central section 11^e is engaged between the end sections 11^d by aligning the tongues 14 with the recesses 15 permitting the central section to be moved laterally into position between the end sections 25 11^d. The end sections 11^d have a thickness greater than the central section 11^e and when this section is in position a space is formed between the adjacent faces of this section and the thin area 10^{cc} into which the stiff member 13 is 30 adapted to be engaged. In this assembled position the screw 16 may be adjusted for tightly bearing against the adjacent face of the stiff member 13 to clamp it in position against the thin area 10^{cc} and maintain the central section 35 11^e in position between the end sections 11^d. In other respects this form of the invention is similar to the previous forms.

40 In Fig. 7 an enlarged reinforcing plate 21 is illustrated with four fastening elements 22 for securing same to the shank portion 23 of the shoe and three additional fastening elements 22' for securing the bent portion 21' of the enlarged reinforcing plate 21 to the heel 10^b of the shoe. By means of this arrangement, the sole, shank 45 and heel portions of the shoe are reinforced and prevent the heel from breaking or cracking from the shank of the shoe.

50 While we have illustrated and described the preferred embodiments of our invention, it is to be understood that we do not limit ourselves to the precise constructions herein disclosed and the right is reserved to all changes and modifications coming within the scope of the invention as defined in the appended claims.

55 Having thus described our invention, what we claim as new, and desire to secure by United States Letter Patent is:

1. In combination with a shoe having a sole 60 extending across the bottom thereof and a heel mounted on said shoe at the back thereof and having a thin area portion attached to said shoe,

a strip of strong material engaged on the adjacent ends of said sole and said thin area portion transversely thereof, and fastening elements securing said strip in position whereby said strip maintains said heel in position on said shoe, the 5 face of said strip which is adjacent said ends being hollowed out between said fastening elements, and a stiff member engaged within said hollow and extending therefrom and engaging said thin area for assisting said strip of strong material in maintaining said heel in position.

2. In combination with a shoe having a sole extending across the bottom thereof and a heel mounted on said shoe at the back thereof and having a thin area portion attached to said shoe, 15 a strip of strong material engaged on the adjacent ends of said sole and said thin area portion transversely thereof, and fastening elements securing said strip in position whereby said strip maintains said heel in position on said shoe, the 20 face of said strip which is adjacent said ends being hollowed out between said fastening elements, and a stiff member engaged within said hollow and extending therefrom and engaging said thin area for assisting said strip of strong 25 material in maintaining said heel in position, said strip being composed of end sections and a central section having tongue elements engaging transverse recesses in the end sections, and means on said central section for engaging 30 against the adjacent face of said stiff member for holding stiff member in position within said hollow and for holding said central section in position between said end sections.

3. In combination with a shoe having a sole 35 extending across the bottom thereof and a heel mounted on said shoe at the back thereof and having a thin area portion attached to said shoe, a strip of strong material engaged on the adjacent ends of said sole and said thin area portion 40 transversely thereof, and fastening elements securing said strip in position whereby said strip maintains said heel in position on said shoe, the face of said strip which is adjacent said ends being hollowed out between said fastening 45 elements, and a stiff member engaged within said hollow and extending therefrom and engaging said thin area for assisting said strip of strong material in maintaining said heel in position, said strip being composed of end sections 50 and a central section having tongue elements engaging transverse recesses in the end sections, and means on said central section for engaging against the adjacent face of said stiff member for holding said stiff member in position within 55 said hollow and for holding said central section in position between said end sections, said means, comprising a set screw engaging through said central section and abutting said stiff member.

LOUIS SABO.
